WELL SWAB

George W. McFarlane, Houston, Tex.

Application October 15, 1937, Serial No. 169,101

2 Claims. (Cl. 103—225)

This invention relates to new and useful improvements in well swabs.

One object of the invention is to provide an improved well swab of what is known as the rapid or fast falling type.

5 A particular object of the invention is to provide an improved well swab having a support provided with full-flowing channels or passages for freely by-passing the liquids and fluids through the swab body or sleeve member, whereby the swab may be rapidly lowered into the liquid at the bottom of the well.

10 A further object of the invention is to provide a well swab including a channeled or grooved mandrel carrying a seat at the lower end of its channel or groove, together with a swab sleeve slidably confined on the mandrel and having a seating face arranged to engage the seat upon the upstroke of the swab, to stop by-passing of the liquids. The swab sleeve having a free sliding movement vertically of the channeled portion of the mandrel to fully open the channel or groove upon the downstroke and to afford a free by-passing of the fluids and liquids.

15 Another object of the invention is to provide a swab sleeve including a metallic liner having a smooth cylindrical bore for freely sliding on a mandrel, as well as having an annular seating face at its lower end, together with an elastic sleeve removably mounted on the liner and arranged to be expanded by the fluid pressure within the liner to cause said sleeve to seal against the inner wall of the tubing or casing in which the swab is being run.

20 A construction designed to carry out the invention will be hereinafter described, together with other features of the invention.

The invention will be more readily understood from a reading of the following specification and by reference to the accompanying drawing, in which an example of the invention is shown, and wherein:

25 Figure 1 is a view, partly in elevation and partly in section, showing a swab constructed in accordance with the invention, the swab sleeve being unseated.

Figure 2 is an enlarged horizontal cross-sectional view taken on the line 2—2 of Figure 1.

30 Figure 3 is a vertical, sectional view of the swab sleeve.

Figure 4 is an enlarged vertical, sectional view of the unloading valve, and

35 Figure 5 is an elevation of a pair of swabs mounted in tandem arrangement.

40 In the drawing the numeral 10 designates an

elongate mandrel, preferably cruciform in cross-section although not necessarily, whereby longitudinal channels or passages 11 are formed on the outer surface of said mandrel by longitudinally extending ribs 10'. The upper end of the 5 mandrel is formed with an enlarged cylindrical head 12 having an axially upwardly extending pin 13, which is provided with screwthreads 13' and is adapted to be screwed into a suitable socket or other suspending means.

45 The channels 11 extend the major portion of the length of the mandrel, terminating at their upper ends in outwardly curved outlets 11', in the head. An annular swab sleeve 15 is mounted to slide vertically on the mandrel. The sleeve 15 is composed of a metallic cylindrical liner 16 which has a plurality of radial ports 17 formed in its midsection. The upward movement of the sleeve is limited by stop shoulders 14 formed by the head overhanging the mandrel.

50 The liner 16 is provided with an enlarged lower end having an upwardly extending flange 18 which forms an annular recess 16' between the flange and the liner, while the upper end of said liner is screw-threaded to receive a lock nut 19. 25 An annular, elastic packer 20, having its ends reduced to form skirts 20', is mounted upon the liner. The lower skirt 20' of the packer engages within the recess 16' formed by the flange 18. For confining the upper skirt of the packer, 30 an annular follower 21 having a depending flange 22 is mounted upon the liner above said packer. The follower 21 is held in position upon the liner by the lock nut 19, and it is apparent that the packer is confined upon said liner between the 35 flanges 18 and 22.

The lower end of the mandrel 10 is provided with a depending screw-threaded pin 23 having an axial duct 24. The duct extends upwardly into the mandrel to communicate with an inclined 40 duct 25, formed in said mandrel and having a port 26 opening into one of the channels 11. A valve case 27, having an internally screw-threaded socket 28, is threaded onto the pin 23, whereby said valve case is secured to the mandrel. 45 The case 27 has a screw-threaded socket 29 and a counter bore 30 which has its lower portion screw-threaded to receive a plug 31.

The upper portion of the bore forms a valve cage 32 which is provided with a radial outlet 50 port 33. A ball or check valve 34 is held in seating position by a helical spring 35 at the upper end of said cage against a valve seat 36. The plug 31 compresses the spring 35 and holds it in position within the cage 32, whereby the ball 55

valve 34 is held in tight engagement with the seat 36. It is noted that the plug regulates the compression of the spring which in turn determines the amount of fluid pressure necessary to unseat the valve. An axial inlet port 37 provided in the upper portion of the valve case 27 establishes communication between the socket 28 and valve cage 32, between the duct 24 and the cage 32 with its outlet port 33. The case is 10 larger in diameter than the mandrel and has its upper end beveled to form a valve seat 38 to receive the beveled valve face 39 formed in the lower end of the liner 16 of the swab sleeve 15.

In operation, the device is connected in the usual manner to a cable or other suspending means and is lowered into a well tubing or casing, either for cleaning purposes or for lifting fluid from the well. As the device is being lowered, the swab sleeve 15 will slide upwardly on the 20 ribs 10' of the mandrel until the lock nut 19 strikes the shoulders 14 which prevents further upward movement of said swab. It will be obvious that when the sleeve strikes the shoulders 14, the outlets 11' will remain open, thus permitting the fluids to freely flow through the channels 11 and by-pass the swab sleeve 15, whereby the swab will readily descend into the well liquids; consequently the device may be rapidly lowered to the desired depth in the liquid standing in 30 the well. The velocity of the downward movement of the swab is much greater than that of the conventional swab due to the by-passing of the liquids and fluids, as has been hereinbefore described.

When the swab reaches the bottom of its run, the swab sleeve will fall or slide downwardly on the mandrel until the valve face 39 of the liner 16 engages the seat 38, to form a closure below the lower ends of the channels 11, which terminate above the lower end of the mandrel. The liquids within the sleeve liner 16 being under a hydrostatic head will exert sufficient force through the ports 17 to expand the elastic packer 20 into engagement with the wall of the casing or tubing whereby the liquids and fluids will not by-pass around the exterior of the swab packer upon the upstroke. The swab assembly may then be raised to the surface and the liquids and fluids thereabove, will be carried upwardly with it, since the weight of the liquids and fluids will hold the face 39 of the liner in tight engagement with the seat 38 of the valve case. This operation may be repeated whenever, and as many times as seems desirable to the operator.

The amount of liquids raised by the swab is predetermined by the compression of the helical spring 32 which is regulated by setting the plug 34. This is a safety device designed to prevent 60 overloading of the swab. When the spring is under the desired compression the excess amount of liquids above the swab will be bled off. This bleeding action is accomplished by a portion of the liquids flowing down through the inclined 65 duct 25 which communicates with one of the channels 11, then into the duct 25 and the inlet port 37, where it will contact the ball valve 34. If there is an excessive amount of liquids above 70 the swab, the weight of said liquids will force the valve from its seat 36, the excess liquids passing thereby and escaping through the outlet port 33. When sufficient liquids have been bled off by this means, the weight will be reduced, thereby permitting the valve 34 to reseat itself 75 and prevent the further escape of said liquids.

It is desirable to have the sleeve liner 16 slide freely up and down the mandrel 10, but no spacing or great clearance between the complementary faces of the ribs 10' and the bore of said liner is required. Therefore there is substantially no side play or lateral movement of the valve sleeve. The liquid being lifted will lubricate the ribs, and so as long as the sleeve slides freely, the necessities of the swab will be met. It is highly desirable for the face 39 to evenly engage the seat 38 and undue lateral movement of the sleeve would interfere with proper seating.

The ribs 10' formed by the channels 11 provide elongate smooth guides for the liner 16 of the swab sleeve and preclude cutting or scoring of the parts, such as is likely to occur where arcuate keys are used, particularly where such keys protrude from the base of the liner and ride on a smooth mandrel. The channels 11 are long enough, preferably being more than twice the length of the swab sleeve 15, to promote free flowing of the by-passing liquids and the swab sleeve has sufficient travel to dislodge or escape any obstruction which may lodge in said channels or at the ends of the sleeve. The outlets 11' are important as they provide a free escape for the liquids and fluids when the swab is descending rapidly.

In Figure 5, a pair of swab assemblies shown 30 mounted in tandem or one above the other, whereby the load of the fluid column is carried by both swab sleeves 15 rather than by one of said sleeves. The amount of fluids raised by each swab is, of course, predetermined by the compression of each helical spring 32. When the weight of the fluid column above the upper swab is excessive, the excess amount is bled off as hereinbefore set forth. The excess fluids and liquids from the upper swab will be caught and carried upwardly by the lower swab. However, it is pointed out that if the weight of these fluids and liquids exceed the compression of the lower helical spring that the excess will be bled off in 40 a similar manner. Thus, if the weight of the fluid column exceeds the compression of both springs, it is obvious that the excess amount will be bled off by the unloading valves. By this arrangement the load carried by each sleeve is 50 limited to a predetermined amount by its unloading valve, whereby the load of the fluid column is evenly distributed so as to prevent overloading of the swabs and, consequently excessive wear of the packers 20.

What I claim and desire to secure by Letters Patent is:

1. The combination with a pair of swabs mounted in tandem including, a pair of elongate mandrels having a channel, a swab sleeve slideable vertically on each mandrel, an enlarged head at the upper end of each mandrel overhanging the channel and forming a stop for the sleeve, valve means for closing the lower end of each channel when said sleeves slide down their respective mandrels to lifting position, the upper end of each channel terminating at the head, and a port communicating with the channel and by-passing the valve means, of an unloading valve carried by each mandrel below said valve means 60 and communicating with the by-pass port, whereby the weight of the fluid load is distributed between the swabs so as to prevent overloading of the same.

2. In combination in a swab, a mandrel hav- 75

ing a plurality of longitudinal channels and a screw threaded pin at its lower end, said mandrel having a drain passage leading from the lower end of one of its channels down through said pin, a swab element slideable longitudinally on said mandrel and having a seat at its lower end,

and a valve case screwed onto said pin and having a stop for receiving the seat of the swab element for closing off said channels to a downward flow and leaving said passage exposed for draining.
